CORNHUSKING MACHINE HAVING A SUC-
TION FAN ABOVE THE HUSKING ROLLS

Milton Hecht, Lakefield, Minn.

Application November 18, 1949, Serial No. 128,130

3 Claims. (Cl. 130—5)

1

This invention relates to a corn-husking machine, and more particularly to an improved machine for removing the husks from the ears of corn as the corn is being conveyed from the snapping rolls of a reaper to the conveyor for disposing the picked corn in a wagon or other suitable storing hopper.

It is an object of this invention to provide a corn-husking machine of the kind to be more particularly described hereinafter, which is especially designed to overcome the difficulties encountered with the conventional husking bed under dry, adverse conditions.

Another object of this invention is to provide a corn-husking device of this kind having vacuum means for disposing of the husks after the husks are removed from the ears. The vacuum means assists the husking rolls in removing the husks from the snapped ears and thereafter removes the husks from the machine through an exhaust or discharge outlet pipe.

Still another object of this invention is to provide a novel husking roll assembly for use with the vacuum husk remover, each of the husking rolls being formed in a manner to suitably contact the ears of corn for removing the husks and formed with confronting, spaced-apart teeth providing a suitable draft passage for the efficient use and operation of the vacuum, husk-removing fan.

A further object of this invention is to provide a corn-husking device of this kind with a vacuum fan acting in the chamber having the husking rolls for removing the loose leaves and husks loosened by the spurred action of the husking rolls. The intake passage of the fan is provided with a suitable damper to prevent light or chaffy corn from being drawn into the fan and subsequently lost. Suitable adjusting means is provided for properly adapting the machine for various field conditions.

With the above and other objects in view, my invention consists in the arrangement, combination and details of construction disclosed in the drawings and specification, and then more particularly pointed out in the appended claims.

In the drawings:

Figure 1 is a top plan view, partly broken away, of a corn-husking machine formed according to an embodiment of my invention;

Figure 2 is a rear end elevation;

Figure 3 is a detailed top plan view of a pair of husking rolls employed in this machine;

Figure 4 is a transverse section taken on a pair of husking rolls, showing the confronting

disposition of the spur teeth in one position of one end of the rolls;

Figure 5 is a transverse section taken on the same rolls as Figure 4, showing the other end of the rolls in the same position with the adjacent rolls in substantial engagement;

Figure 6 is a top plan view, partly broken away, of the perforated floor of the corn chute;

Figure 7 is a fragmentary detailed section, taken on the line 7—7 of Figure 1, showing the disposition of the damper in the air passage leading from the cover to the fan;

Figure 8 is a sectional view taken substantially on the line 8—8 of Figure 1, Figure 9 is a sectional view taken substantially on the line 9—9 of Figure 8, and Figure 10 is a transverse sectional view taken substantially on the line 10—10 of Figure 8.

Referring to the drawings, the numeral 10 designates generally a corn-husking machine constructed according to an embodiment of this invention for attachment between the snapping roll assembly 11 and the conveyor 12 which conveys the snapped ears of corn to a wagon, not shown in the drawings, or other suitable hopper or storage for the husked corn.

The entire assembly of the snapping roll assembly 11, the husking machine 10 and the conveyor 12 are suitably supported on a mobile frame 14 having supporting wheels 15 rotatably mounted thereon. The frame 14 is provided with a suitable drawbar or drawbar section 16 for connection to a tractor or other suitable towing vehicle having a power take-off assembly for driving connection to the moving parts of the various sections of the entire assembly or unit 17.

The snapping roll assembly 11 is supported on one side of the frame 14 and may be of a generally-conventional arrangement extending downwardly and forwardly of the frame 14. The rear end of the snapping roll assembly is supported in a raised position on the rear end of the frame, and suitable conveyor means 18 are provided in the spaced-apart members 19 for carrying the snapped corn to the upper rear end of the assembly where the ears of corn are suitably deposited to be subsequently husked and placed in a wagon conventionally assisting the harvesting of the corn.

The snapped corn conveyor 12 is supported on the frame 14 opposite from the snapping roll assembly 11 for raising the husked corn to be dropped into the wagon. The conveyor 12 may be of any conventional structure and formation, having the lower end positioned forwardly on the

frame 14 transversely from raised rear end of the snapping roll assembly 11. The conveyor 12 extends upwardly and rearwardly of the frame 14 with the upper rear end positioned in a raised manner, whereby a suitable truck or wagon may be positioned thereunder for collecting the picked and husked corn.

The husking machine 10, formed according to an embodiment of this invention, is positioned between the snapping roll assembly 11 and conveyor 12 for husking the corn between the time it has been picked and the time it is placed in the wagon, not shown in the drawings.

The husking machine 10 is formed with an inclined corn chute 18 extending transversely of the frame 14 between the upper end of the snapping roll assembly 11 and the lower end of the conveyor 12. The bottom wall 19 of the chute 18 is perforated to permit the free passage of air therethrough in a manner and for the purpose to be more particularly described hereinafter. The side walls 20 of the husking machine extend upwardly from the side edges of the bottom wall 19 and are bowed over above the bottom wall 19 to define the top wall or the cover 21 spaced above the perforated bottom wall defining a substantially closed housing having openings at the opposite ends of the bottom wall for receiving corn to be husked and corn after it has been husked.

A plurality of husking rolls 22 are supported in the chute 18 above the bottom wall 19. The rolls 22 are rotatably journaled between a pair of side frame members 24 extending along the length of the bottom wall 19 and spaced thereabove. One end of each of the side frame members 24 is adjustably secured on the frame 14 for selected adjustment in relation to the bottom wall 19. A pair of braces or arms 25 are fixed on one end of the frame 14 and extend upwardly adjacent the inner side of the snapping roll assembly 11. An outwardly extending arm 26 is fixed on the upper end of each of the side frame members 24 for adjustable engagement with the respective braces 25. The braces 25 are each formed with a plurality of spaced apart apertures 27 for receiving bolts 28 for securing the upper ends of the frame members in a selected position.

The lower ends of the frame members 24 are adjustably supported on the main frame 14. A transverse bar 28 is fixed between the lower ends of the frame members opposite ends 29 of which extend outwardly beyond opposite sides of the side bars 24 and are pierced to receive vertical screws 29' which are mounted for rotation in the frame 14 adjacent the conveyor 12. Lower springs 30 are carried by the frame 14 in encircling relation to the screws 29' beneath the opposite ends 29 of the bar 28 for cushioning the lower ends of the frame members 24. Upper springs 31 rest on the end extensions 29 and encircle the screws 29' and seated on the upper ends of the springs 31 is a pressure bar 31' carrying adjacent opposite ends internally threaded bushings 29a which threadedly engage the screws 29'. Crank handles 34 are engaged on the upper end of the screw 29' for rotating the screw 29' and thereby vertically adjusting the pressure bar 31' and thereby moving the lower end of the roller-supporting frame members 24 to selected positions against the effort of the springs 30 and 31.

The husking rolls 22 are positioned transversely of the corn chute 18 for engaging the corn positioned between the rolls 22 and bottom wall 19. Each of the rolls 22 has a gear 35 fixed on one end for engagement with a similar gear 35 75 49 on the other end. Spaced apart, spur-toothed

on an adjacent roll for unitary, timed rotation of all of the rolls. A drive shaft 36 is rotatably carried by the frame 14 for attachment to a power take-off of a towing tractor or other suitable power means. A sprocket 37 is driven by the shaft 36 and is engaged by a chain or flexible member 38. Another sprocket 39 is fixed on a shaft 40 of one of the husking rolls 22 and also engages the flexible member 38 for rotating the rolls 22 upon rotation of the drive shaft 36.

While the inclination of the corn chute may be sufficient for moving the snapped ears of corn downwardly by gravity to the unloading conveyor 12, I employ a suitable conveyor 41 having transversely extending longitudinally spaced flights 41' moving along the bottom wall 19 below the rolls 22 for moving the ears of corn between the side walls 20. The conveyor 41 is driven by a suitable chain or drive connection 42 connected to the driving means 36 for rotating the rolls 22. While the driving means for the corn husking machine is shown in the drawings as including separate drive shaft elements connected together by suitable universal joints, it is understood that a single straight shaft or other conventional driving means may be employed to suit the particular frame on which the device may be mounted.

The chute between the snapping roll assembly 11 and the discharge conveyor 12 is noted in the drawings as declining and this angle may be changed to a horizontal or upwardly inclined position, the angle being dependent upon the particular corn-husking machine 11 being used.

The rolls 22 are adapted to engage the corn on the upper side and are rotated in a manner to pull the leaves upwardly between pairs of rollers. For removing the husks from the corn chute 18, a vacuum fan or blower 44 is connected to the upper portion of the casing 20.

A suitable fan inlet tubing or conduit 45 is connected to the upper end of the top wall 21 and communicates with the interior of the chute 18 at one end and the inlet side of the blower 44 at the other end. A proper discharge conduit or pipe 46 extends from the exhaust side of the blower 44 rearwardly of the frame 14 for discharging the corn husks from the machine 10, as it is pulled through a corn field.

In order to provide for the proper air flow through the husking machine 10, the rolls 22 are modified from the conventional style of husking rolls used in prior devices employed in husking corn.

The husking rolls 22 of this machine 10 are disposed in abutting pairs, rotating upwardly at their abutting edges and formed with cutout sections confronting the adjacent roll to permit the free flow of air as effected by the blower 44. All of the husking rolls 22 are formed in the same manner, so a detailed description of one will suitably apply to each of the others.

The husking roll 22 is generally cylindrical in configuration, being made of metal, wood or other suitable material. One half 48 of the length of the cylindrical roll body 47 is formed as a semi-cylindrical solid body having a plurality of semi-cylindrical, longitudinally spaced apart members 49 on the other side thereof, as clearly shown in Figure 3 of the drawings. The spaced apart members 49 are formed with radially arranged spur teeth 50. The other end of the cylindrical body 47 is formed in exactly the same manner as the portion described above with the solid portion 48a disposed in alignment with the members 49 on the other end. Spaced apart, spur-toothed

members 50a are formed on the other side of the solid body portion 48a in longitudinal alignment with said body portion 48 of the other end of the same roll.

As the rolls 22 are disposed in pairs, each pair of rolls 22 are positioned and timed in rotation, whereby the spaced spur members of one roll will confront the spaced spur members of the other roll during the timed rotation, and the solid body portions will abut. The spur members of one roll of each pair are transversely aligned with the spur members of the abutting, confronting roll, so that the confronting spur teeth will engage at their tips during the operation of the machine and the spaces between the spur members will provide for the free flow of air upwardly through the apertured bottom wall 19, between the husking rolls, through the conduit 45, the blower 44 and out the discharge conduit 46.

A pulley or sprocket 51 is rotated by the drive shaft 36 and engages a belt 52. The belt 52 is also trained about the pulley 54 which is fixed on the rotatable shaft 55 which carries the fan blades.

In order to prevent the blower 44 from discharging light corn from the machine 17 along with the corn husks, a suitable damper 56 is rockably mounted in the blower inlet conduit 45. A suitable adjusting crank or screw 57 is engaged through the conduit 45 and is connected to the damper for varying the size of the opening through the conduit.

In the use and operation of the corn-husking machine 17, the snapping roll 11 and conveyor 12 may be driven or actuated in any conventional manner. As the ears of corn are moved down the corn chute 18 between the husking rolls 22 and the apertured wall 19, the rolls will strip the husks from the corn and the suction in the corn chute 18 will discharge the husks out through the discharge port or conduit 46.

The shakers, shaker screens and shell corn augers in use on conventional styles of husking beds currently in use are dispensed with in the structure, use and operation of this machine, as such elements are not required.

I do not mean to confine myself to the exact details of construction herein disclosed, but claim all variations falling within the purview of the 50 appended claims.

I claim:

1. A corn husking machine comprising a foraminous surface along which harvested corn ears move in a path in a single layer, husking 55 rolls mounted above said surface for rotation in juxtaposed relation about axes extending transversely of the path to strip the husks from the corn ears supported by said surface, a hood carried by the surface and extending upwardly 60 therefrom and over the husking rolls, and means carried by the hood and communicating with the interior thereof for creating a draught of air upwardly through said surface and between the husking rolls and removing from the husking 65

rolls husks stripped from corn ears moving along the surface.

2. A corn husking machine comprising a foraminous surface along which harvested corn ears are advanced in a single layer, a frame mounted adjacent one end of the surface to move in a vertical arcuate path above the surface, adjustable means mounted adjacent the opposite end of the surface and engaging the frame for yieldingly supporting it at a selected position above the surface and movement in the vertical arcuate path, husking rolls carried by the frame for rotation in juxtaposed relation about axes which extend transversely across the frame, a hood carried by the surface and extending upwardly therefrom and over the husking rolls, and means carried by the hood and communicating with the interior thereof for creating a draught of air upwardly through the surface and between the husking rolls and removing from the husking rolls husks torn from corn ears moving along the surface.

3. A corn husking machine comprising an upwardly inclined foraminous surface down 25 which harvested corn ears are adapted to advance in a single layer, a frame mounted adjacent the upper end of the surface to move in a vertical arcuate path above the surface, adjustable means mounted adjacent the lower end of the surface and engaging the frame for yieldingly supporting it at a selected position above the surface for movement in the vertical arcuate path, husking rolls carried by the frame for rotation in juxtaposed relation about parallel axes 30 which extend transversely across the frame, a hood carried by the surface and extending upwardly therefrom and over the husking rolls, and means carried by the hood and communicating with the interior thereof above the husking rolls 35 for creating a draught of air upwardly through the surface and between the husking rolls and removing husks torn from corn ears advancing along the surface.
